(57) **CLAIM**

The ornamental design for a shotgun sight enhancer, as shown and described.

DESCRIPTION

FIG. 1 is a perspective view of a shotgun sight enhancer;

FIG. 2 is a bottom plan view thereof;

FIG. 3 is a top plan view thereof;

FIG. 4 is a front elevational view thereof;

FIG. 5 is a rear elevational view thereof;

FIG. 6 is a left-side elevational view thereof; and

FIG. 7 is a right-side elevational view thereof; and,

FIG. 8 is a perspective view of a shotgun sight enhancer mounted on a shotgun.

The broken line showing of a shotgun is for the purpose of illustrating environmental structure and forms no part of the claimed design.
